UNITED STATES PATENT OFFICE

171,241

PITCHER OR SIMILAR ARTICLE

A Baker Barnhart, New York, N. Y.

Application April 22, 1953, Serial No. 24,628

Term of patent 7 years

(Cl. D44—21)

To all whom it may concern:

Be it known that I, A Baker Barnhart, a citizen of the United States, residing in city of New York, State of New York, have invented a new, original, and ornamental Design for a Pitcher or Similar Article, of which the following is a specification, reference being had to the accompanying drawing, forming a part hereof.

Fig. 1 is a side elevational view of a pitcher or similar article showing my new design;

Fig. 2 is a front elevational view thereof;

Fig. 3 is a top plan view thereof.

I claim:

The ornamental design for a pitcher or similar article, as shown.

A BAKER BARNHART.
